[57] CLAIM

The ornamental design for a house sculpture toy figure,
as shown and described.

DESCRIPTION

FIG. 1 is a front elevational view of a house sculpture
toy figure showing my new design;
FIG. 2 is a right side elevational view thereof, the left
side being a mirror image;
FIG. 3 is a rear elevational view thereof;
FIG. 4 is a reduced scale top view; and
FIG. 5 is a reduced scale bottom view.
